PROTECTIVE SPORTS HELMET

Harmey S. Hyatt, Jr., General Delivery,
Albemarle, N.C. 28001

Filed Mar. 6, 1972, Ser. No. 232,346

Term of patent 14 years

Int. Cl. D2—03

U.S. Cl. D2—232

FIG. 1 is a front perspective view of a protective sports helmet showing my new design;

FIG. 2 is a rear perspective view thereof;

FIG. 3 is a front elevational view on a reduced scale;

FIG. 4 is a side elevational view taken from the right of FIG. 3;

FIG. 5 is a top plan view thereof; and

FIG. 6 is a rear elevational view.

I claim:

The ornamental design for a protective sports helmet, as shown.
